UNITED STATES PATENT OFFICE

OTTO M. SUMMERS, OF DAYTON, OHIO, ASSIGNOR TO FRIGIDAIRE CORPORATION, OF DAYTON, OHIO, A CORPORATION OF DELAWARE

PUMP FOR REFRIGERATING APPARATUS

Application filed February 29, 1928. Serial No. 257,818.

This invention relates to improvements in valves and means for mounting the same and more particularly the outlet valves used for compressors and the like.

5 It is one of the objects of the invention to provide an improved valve plate which is formed of a single stamped member.

It is another object of the invention to simplify the construction and to reduce the cost 10 of manufacture of the valve plate.

It is a further object of the invention to provide a valve plate which can be installed with a minimum of expense and difficulty and which can be manufactured without grinding 15 or special finishing operations.

With these objects in view the invention contemplates providing an improved valve plate which is stamped or punched out of a single sheet of metal in the manner herein described.

20 Further objects and advantages of the present invention will be apparent from the following description, reference being had to the accompanying drawing, wherein a preferred 25 form of the present invention is clearly shown.

In the drawings:

Fig. 1 shows a view in section of the improved valve plate of the invention mounted 30 in position in a compressor;

Fig. 2 shows a top view of the valve plate itself, and

Fig. 3 is an enlarged cross-section of a section through the compressor and the valve 35 plate.

In the construction of compressors, particularly of the type used in mechanical refrigerators, it is customary to mount the outlet valves thereof on plates which are clamped 40 between the head of the cylinder and the body thereof. Such valve plates are generally made of cast iron and it is always necessary to machine the surfaces of such plates very accurately, particularly at the points 45 where the valves are mounted and at the portions of the plate clamped between the head and the body of the cylinder. Such machining operations are relatively expensive and it is an object of the present invention 50 to obviate the necessity for such work.

Another problem confronting the designers of compressors is the dissipation of heat caused by the compression of the gas. In general this has been taken care of by the provision of fins on the compressor body and head. Under heavy loads, the fins have not 55 always been sufficient and the compressor has become hot around the valve plate due to high head pressures and hot oil. This heat, pressure and oil has sometimes affected the gas- 60 kets around the valve plate.

The improved valve plate of this invention is made of a piece of sheet steel of suitable thickness which is punched or stamped out of a large sheet. This sheet should have two 65 plane surfaces so that the necessity for machining the same is obviated. The punching or stamping operation is necessarily made by a very powerful machine. The force with which the valve plate is separated from the 70 sheet of steel causes a deformation about the edge of the valve plate. One of the chief objects of this invention therefore consists in so punching the valve plate out of a sheet of steel that the portions thereof which may be strained or deformed during the punching operation lie outside of the limits of the surface constituting the valve retaining portion and the portion clamped between the cylinder body and head. This outer projecting section of material constitutes a heat radiating 75 fin projecting from what is normally the hot- 80 test place of the compressor during operation.

Referring in detail to the drawings, it will be observed from Figs. 1 and 3 that the valve plate consists of a sheet metal member 10 which, as shown in Fig. 2, is stamped out in the form of a substantially oval plate large enough to cover the cylinder of a compressor. In the drawings the compressor is represented 85 as having two cylinders, 11 and 12, in which pistons 13 and 14 operate respectively. However, it is obvious that the plate of the invention is applicable to single cylinders or to a plurality of cylinders and that it may 90 have any shape corresponding to such cylinders. The plate may be of any suitable thickness, although by way of illustration $\frac{1}{4}$ inch may be considered a preferred dimension. This thickness of $\frac{1}{4}$ inch is approximately half of 95 100

the safest thickness allowable with a cast iron plate due to the possibility of blow holes in the cast iron.

A head member 15 is provided which is clamped to the cylinder bodies by means of suitable bolts 16 which pass through the head 15, the extremity of the valve plate 10 and into the threaded portion 17 of the cylinders. The stressed or deformed portion of the plate 10 extends somewhat beyond the walls of the cylinder and forms a projecting fin 18 which aids in radiating heat in a manner analogous to the fins 27 on the cylinder body. This projecting fin 18 is integral with interior of the plate located in the hottest place of the compressor. The compression of the gas and the hot oil create quite a large amount of heat on the plate just above the pistons and the fin 18 allows a direct conduction to the outside air. This fin projects outwardly from the exterior of the cylinder body and may slant downwardly as shown in Figs. 1 and 3. This downwardly slanting portion represents the amount of deformation produced during the stamping of the valve plate from a sheet of metal and it is the purpose of the invention to mount the valve plate in such a manner that this deformed or stressed portion lies outside of the compressor itself so that only the plane and unstressed portions of the plate itself will come within the confines of the cylinder. The amount of such deformation depends of course upon the nature of the steel used and the condition of the dies employed. Its exact degree of curvature is of no consequence, but as shown in Fig. 3 by the dotted line 19 which is a prolongation of the top plane surface of the valve plate the deformed portion may extend outwardly to a considerable extent.

The valve plate of the invention as before described, is clamped between the cylinder head 15 and the body portions 11 and 12 of the cylinder. Suitable gaskets 20 are disposed between the head and the plate and the cylinder body and plate to prevent leakage.

The valve plate is provided with holes 21 which are drilled therein to accommodate the bolts 16 which hold the cylinder head and valve in assembled relation and is also provided with valve seats 24 formed by under cutting a recess 23 in the top surface of the valve plate and leaving projecting a seat 24 for the valve which should present a flat surface to the valves and which may be secured by stoning or lapping the same if necessary. Such a ridge to constitute a satisfactory valve seat should be quite narrow, $\frac{1}{2}$ inch being a suitable width, so as to prevent slapping of the valve against the plate and improper seating of the valve. The valve structure constituting valve reed 26 and spring 25 may be held to the valve

plate by means of screws 24 threaded into the valve plate.

By means of the improved valve plate of the invention considerable economy may be effected in the construction of compressors. Not only is the necessity for costly machining operations obviated but by using sheet steel a thinner plate may be used than is the case of cast iron. While the valve plate according to the invention is more easily and economically manufactured than the usual valve plate, yet one of its most important advantages is the fact that it allows a direct conduction of heat from one of the hottest places in the interior of the compressor.

While the forms of embodiment of the invention as herein disclosed constitute a preferred form it is to be understood that other forms might be adopted, all coming within the scope of the claims which follow.

What is claimed is as follows:

1. A valve plate for a compressor or the like comprising a flat sheet metal plate stamped out of a sheet of metal and having valve seats formed thereon arranged to be covered by valves and being shaped to be mounted between the cylinder head and the cylinder body of a compressor and having the zone of deformation caused by said stamping operation located outside of the effective valve plate area and constituting a heat radiating fin.

2. In a compressor, a stamped sheet metal plate arranged to be interposed between surfaces having the same shape as the opposed sides of the plate, said plate having its zone of deformation which is caused by the stamping thereof, disposed beyond the engaging area of the plate and such surfaces and constituting a heat radiating fin.

3. In a compressor or the like, in combination, a cylinder, a head for said cylinder and a valve plate clamped between said head and said cylinder, said valve plate being punched out of a single sheet of sheet metal and having its zone of deformation extending outside of the effective valve plate area clamped between said head and said cylinder, said outside zone constituting a fin for the conduction of heat from said cylinder and head.

4. In a compressor, in combination, a cylinder, a head for said cylinder, a valve plate intermediate said cylinder and said head, means for uniting said head, said plate and said cylinder into assembled relation, said means being located adjacent the circumference of said cylinder, said valve plate having a peripheral zone which is apt to be deformed extending outside of the valve plate area included between said head and said cylinder and arranged to radiate heat from said cylinder and head.

5. In a compressor, in combination, a cylinder body, a head for said cylinder, a valve plate intermediate said cylinder and said

head, means for uniting said head, said plate and said cylinder into assembled relation, said means being located adjacent the circumference of said cylinder, said valve plate having a peripheral zone of deformation extending outside of the valve plate area included between said head and said cylinder, said deformed zone extending substantially beyond said cylinder and serving as a heat radiating fin.

5 6. In combination, a cylinder, a head for said cylinder, a valve plate intermediate said head and cylinder, said valve plate being stamped from sheet material and having a portion of its peripheral zone of deformation projecting beyond the periphery of said head and cylinder.

10 7. In combination, a cylinder, a head for said cylinder, a flat valve plate interposed between said cylinder and said head, said cylinder and said head being provided with flat surfaces engaging the flat surfaces of the valve plate, said valve plate being stamped out of a sheet of metal and having its zone of deformation due to said stamping operation disposed beyond the engaging surfaces of said head and said cylinder.

15 8. In a compressor having a cylinder, means for dissipating heat of compression including a thermally conducting plate extending from within the cylinder outside of the cylinder and remote from parts adjacent the plate.

20 9. In a compressor in combination, a cylinder, a discharge chamber and a partition separating the cylinder and chamber, said partition having a passage therethrough and being of metal of high thermal conductivity and having a portion extending outside of the cylinder and remote from parts adjacent the plate.

25 In testimony whereof I hereto affix my signature.
